Patented July 29, 1919.

UNITED STATES PATENT OFFICE.

ERNEST F. WIEDERHOLDT, OF ST. LOUIS, MISSOURI.

SILO.

1,311,366.

Specification of Letters Patent. Patented July 29, 1919.

Application filed July 12, 1915. Serial No. 39,396.

To all whom it may concern:

Be it known that I, ERNEST F. WIEDERHOLDT, a citizen of the United States, residing at St. Louis, Missouri, have invented a certain new and useful Improvement in Silos, of which the following is a full, clear, and exact description, such as will enable others skilled in the art to which it appertains to make and use the same, reference being had to the accompanying drawings, forming part of this specification.

My invention relates to silos, the principal objects of my invention being to construct a comparatively simple and inexpensive silo wall of interlocking brick or tile, the same being formed so as to resist to a maximum degree the stresses produced by the weight of the contents of the silos; to form in the silo wall constructed as just described an elongated vertically disposed opening or a vertical row of openings which permits the delivery of the ensilage to and from the silo; to provide suitable ties across the opening or openings in the silo wall which ties, in effect, serve the same purpose as the interlocking brick or tile in maintaining the entire wall in tension and transmitting stresses from the wall at one side of the opening to the other; to provide simple means for reinforcing the edges of the opening or openings; to provide simple means for tying each course of brick or tile in the wall to the reinforcements at the sides of the opening; to provide simple and easily operated doors for the opening or openings in the wall, and further to generally improve upon and simplify the present types of silos and like structures and materially decrease the cost of construction thereof.

It will be understood that the walls of silos and like structures as ordinarily built are provided with an elongated vertically disposed opening or a vertical row of openings, the same being necessary to permit the ensilage to be readily removed as it is used.

The weight of the contents of a silo exerts outward pressure upon the silo wall and consequently the latter is, when filled or partially filled, constantly in tension; and the strength of the wall to resist the stresses thus produced is to a considerable extent

weakened by reason of the openings which are necessary to discharge the contents.

Interlocking brick or tile produce an ideal silo wall by reason of the fact that said wall can be easily and cheaply erected and the interlocked members forming said wall afford a high degree of resistance to stresses produced by the weight of the ensilage, but in so far as I am aware interlocking members have never been utilized for producing silos for the reason that no practical way has been found to provide the necessary openings in the wall without greatly weakening the structure.

By my improved construction of reinforcing the sides of the openings in the wall, tying the edges of the wall forming members to said reinforcing means, and arranging ties across said opening, I am able to produce a silo or like structure which has great strength and stability, which will readily withstand the stresses produced by the weight of its contents, and which can be erected at comparatively small cost.

With the foregoing and other objects in view my invention consists in certain novel features of construction and arrangement of parts, hereinafter more fully described, claimed and illustrated in the accompanying drawings, in which—

Figure 1 is an elevational view of a silo constructed in accordance with my invention.

Fig. 2 is an elevational view of a portion of a silo and showing the doors which normally close the opening in the silo wall.

Fig. 3 is a vertical section taken approximately on the line 3—3 of Fig. 2.

Fig. 4 is a horizontal section taken approximately on the line 4—4 of Fig. 2.

Fig. 5 is a fragmentary view in perspective of a portion of one of the reinforcing members at the side of the opening in the silo wall and showing the means employed for tying the edge of the wall to said reinforcing member.

Fig. 6 is an enlarged vertical section taken approximately on the line 6—6 of Fig. 4.

Fig. 7 is a detail elevational view of a portion of one of the reinforcing members at the side of the opening in the silo wall

and showing the loops which receive the wall ties.

In the drawings I have illustrated the silo wall constructed of interlocking brick, the 5 same being laid in courses and each brick comprising a substantially rectangular body portion 10 provided on one side and at each end with a vertically disposed rib such as 11. The inner faces of these ribs are slightly 10 inclined or under-cut and when the bricks are properly assembled or laid with a double row in each course the ribs 11 at the adjacent ends of a pair of bricks in the outer row occupy the space between the ribs of a 15 brick in the inner row.

It will be understood, of course, that the bricks are laid with mortar, cement, or other self-hardening bonding material.

The silo wall thus constructed is provided 20 with a vertically disposed opening and arranged on the edges of the wall at the sides of this opening are posts, preferably in the form of vertically disposed channels, 12, the flanges of which overlie the inner and 25 outer faces of the edges of said wall. (See Fig. 4.)

Secured to the face of the web of each channel between the flanges thereof are horizontally disposed loops 13, there being one 30 of these loops for each course of the interlocking brick or tile.

The means employed for tying the edges of the wall to the channels 12 comprises substantially inverted U-shaped anchoring members 14, preferably formed of metal and as 35 the courses of brick or tile are laid one upon the other, these anchoring members are placed in position with one leg inserted through the corresponding loop 13 and the 40 other leg positioned between the overlapping ribs or flanges 11 of the adjacent pair of brick or tile. (See Figs. 5 and 6.) Thus, the ends of each course of interlocked brick or tile forming the wall are effectively tied 45 to the reinforcing channels 12 and the latter are tied to each other by transversely disposed rods 15, the end portions of which 50 pass through the webs of said channels 12. Each of these tie rods is provided with a nut on its ends or with a head on one end and a 55 nut on the other, and positioned on each rod between the channels 13 is a spacing member 16, preferably formed of tubing. These tie rods act as tensioning members to transmit 60 stresses from one side of the opening to the other and in effect serve the same purpose as the interlocking brick or tile which would occupy the opening in case the silo were built with a solid imperforate wall.

60 Fixed in any suitable manner to the webs of the channels 12 and projecting into the opening between said channels are door stops 17, preferably in the form of ordinary metal angles and bearing against the edges

thereof are removable doors 18 of either 65 wood or metal.

Passing through the central portion of each door is a bolt 19, the outer portion of which passes through the center of a transversely disposed door fastening bar 20, preferably 70 in the form of a channel, the ends of which bear upon the outer flanges of the channels 12.

The projecting end of the bolt 19 is threaded and receives a winged nut 21 which, when 75 tightened on said bolt, draws the door against stops 17 with the side edges of said door fitting snugly against the inner portions of channels 12.

In Fig. 1 I have shown the usual sheet 80 metal chute 22 positioned over the opening in the silo wall, which chute is utilized when the contents of the silo are being removed. This chute is of ordinary construction and forms no part of my invention.

While I have illustrated and described the wall of the silo as being constructed of interlocking brick, it will be understood that practically the same structure can be produced with interlocking tile.

A silo of my improved construction is comparatively simple, can be erected with comparatively little cost and while the wall of the silo is provided with the necessary opening to permit the contents of the silo to 90 be readily discharged, the strength of the wall is in nowise impaired, owing to the effective manner in which the edges of the wall are tied to the reinforcing members at the sides of the opening and the manner of 95 tying said reinforcing members to each other.

This construction maintains the entire wall in tension and effectively resists the 100 stresses produced by the weight of the contents of the silo.

My improved structure while particularly adapted for silos can be advantageously employed in any container or structure, the wall of which is provided with an opening or openings, and it is desired to reinforce 110 and tie said wall across such opening.

It will be readily understood that minor changes in the size, form and construction of the various parts of my improved silo can be made and substituted for those herein 115 shown and described, without departing from the spirit of my invention, the scope of which is set forth in the appended claims.

I claim:

1. The combination with a silo wall provided with an opening, of posts positioned at the sides of the opening, loops on said posts, inverted U-shaped members, the inner legs of which engage in said loops, and means on the wall for receiving the outer legs of said 120 inverted U-shaped members.

2. The herein-described silo having a wall composed of inner and outer courses of in-

terlocked blocks, said wall being provided with an opening, posts at the sides of said opening, flanges on said posts, which flanges engage the blocks immediately adjacent to the sides of the opening, and U-shaped members for tying the engaged blocks to said posts.

In testimony whereof I hereunto affix my signature in the presence of two witnesses, this 8th day of July, 1915.

E. F. WIEDERHOLDT.

Witnesses:

M. P. SMITH,
W. A. HANDEL.
